Primary Examiner — T. Chase Nelson*Assistant Examiner* — Jonathan J Han(74) *Attorney, Agent, or Firm* — Brian S. Steinberger; Law Offices of Brian S. Steinberger, PA(57) **CLAIM**

The ornamental design for a firearm bipod, as shown and described.

DESCRIPTION

FIG. 1 shows an upper front right perspective view of the novel firearm bipod with bipod in retracted position with screw clamp.

FIG. 2 is an upper rear left perspective view of the firearm bipod of FIG. 1.

FIG. 3 is a lower rear right perspective view of the firearm bipod of FIG. 1.

FIG. 4 is a lower front left view of the firearm bipod of FIG. 1.

FIG. 5 is a right side view of the firearm bipod of FIG. 1.

FIG. 6 is a left side view of the firearm bipod of FIG. 1.

FIG. 7 is a front view of the firearm bipod of FIG. 1.

FIG. 8 is a rear view of the firearm bipod of FIG. 1.

FIG. 9 is a top view of the firearm bipod of FIG. 1; and,

FIG. 10 is a bottom view of the firearm bipod of FIG. 1. The broken lines in FIGS. 1 to 10 are for purposes of illustrating portions of the firearm bipod that form no part of the claimed design.

1 Claim, 5 Drawing Sheets(56)
